UNITED STATES PATENT OFFICE.

JOHN C. MILLER, OF CINCINNATI, OHIO.

DESIGN FOR A RING.

SPECIFICATION forming part of Design No. 36,274, dated April 7, 1903.

Application filed March 7, 1903. Serial No. 146,767. Term of patent 7 years.

To all whom it may concern:

Be it known that I, JOHN C. MILLER, a citizen of the United States, residing at Cincinnati, in the county of Hamilton and State of Ohio, have invented and produced a new, original, and ornamental Design for a Ring, of which the following is a specification.

My invention relates to a new and ornamental design for a ring particularly adapted to a secret order.

The features of the invention are illustrated in the figure of the drawing accompanying the specification, of which the following is a description.

15 A represents a ring.

B represents an eagle in full relief on the front of the ring.

C represents enamel strips for color effect upon each side of the eagle.

The feature of the ornamentation is a single-headed eagle with wings half outspread, the oval portion of the upper extremity of the wings terminating flush with the upper edge of the ring and throwing the head into full relief. Likewise the tips of the wings and the tip of the tail are drawn out to sharply-turned angles flush with the bottom edge of the ring, showing the feet, claws, tip of the tail, and tip of the wings in bold relief.

Having described my invention, I claim— 30

The ornamental design for a ring, substantially as herein shown and described.

In testimony whereof I have hereunto set my hand.

JOHN C. MILLER.
